HAMLET JOHN WILSON, OF ALTRINCHAM, ENGLAND

TREE FOR FOOTWEAR

Application filed October 2, 1928, Serial No. 309,734, and in Great Britain March 21, 1928.

This invention relates to an improved tree for boots, shoes or the like.

There is a boot tree already in common use in which the toe-piece is connected to a heel piece through the medium of pivoted rods which engage with each other by means of a central sliding member and are secured by a pin and socket mechanism or a plate and slot mechanism. The spacing apart of the toe-piece and heel-piece is regulated by such mechanism but in practice the results are not always satisfactory since difficulty arises in sliding the rods with respect to each other, and also if the tree is inserted rather tightly there is a tendency for the connecting rod to sag to one side or the other so deforming the shape of the boot or shoe. Various modifications of such devices have been proposed including the use of a screw threaded central rod to space away the toe-piece and heel-piece.

In another form of device proposed the heel-piece and the toe-piece themselves were made of such substantial dimensions as almost to fill the entire shoe and were spaced apart by a screw thread or rack and pinion mechanism.

According to one feature of the present invention I provide a tree for boots or shoes formed of a toe-piece, a heel-piece and an operating member secured between the two adapted to fill up the whole width of the boot or shoe and provided with mechanism for progressively spacing apart the toe-piece and heel-piece. By thus providing an operating member which is separable from the toe-piece and preferably also from the heel-piece it is possible to utilize a toe-piece of any suitable size without corresponding variation of the central operating member which can be used for several sizes of feet. At the same time the width of the operating member tends to prevent creasing of the leather at the sides of the shoes and to prevent deformation due to indirect thrust between the toe-piece and heel-piece.

According to another feature of the invention I provide a tree for boots and shoes formed of a toe-piece, a heel-piece and an operating member secured between the two adapted by the provision of a spiral thread on a plate member meshing with a slot or slots to

space apart the toe-piece and heel-piece to the desired extent. Preferably the toe-piece is pivotally mounted on an extending member which is provided with a rack meshing with the spiral thread in the operating member. The toe-piece and the heel-piece may readily be replaced by others of different size if desired. The heel-piece is preferably adjustable and may be provided with a screw threaded shank and lock nut for this purpose. Preferably the toe-piece and heel-piece are mounted on horizontal pivots to facilitate insertion in the shoe and to enable the tree to take up its correct position in the shoe.

The mechanism including a spiral thread on a flat plate meshing with a rack or slot on a bar is particularly simple, compact and economical and is very effective in operation to enable the tree to be used as a stretcher if desired. By turning the operating plate with a key or handle the toe-piece and heel-piece can be spaced apart to any desired extent and will remain in the set position as long as required.

A preferred form of the invention will now be described with reference to the accompanying drawings in which:

Figure 1 shows a sectional elevation of a tree constructed in accordance with the present invention;

Figure 2, is a plan view partly in section without the operating key, and

Figure 3 is an inverted plan view of the operating member.

In the drawing the toe-piece 1 is secured by rivets 2 to a bifurcated connection 3 pivoted at 4 to an extension strip 5. The inner end of this extension strip 5 is formed as a rack with teeth 6 and projects into the main casing 7. It is suitably guided by a cover 23 secured by screws 24 to the casing 7. A pin 8 on the cover 23 engages a longitudinal slot 9 in the strip 5 to prevent sagging.

A rotatable plate 10 is provided with a bushing 11 stepped into the casing 7, and a spiral thread 15, preferably of Archimedean form which engages the teeth 6 of the rack. An operating handle 16 is connected to upstanding projections 18 of the bushing 11 by a pivot pin 17. This permits the handle 16

to pivot as shown to the dotted position when not in use.

The heel-piece 19 is secured by a pivot 20 to the casing 7.

5 The invention is not, of course, limited to the form of construction shown since various modifications may be made without departing from the scope of the invention as defined in the appended claims. Thus the operating 10 handle may be in the form of a detachable key. It may also be bifurcated and fitted over the bush of the rotatable plate member, being secured by a pin to enable it to drop when not in use. The toe-piece and heel- 15 piece may be of skeleton form if desired.

I declare that what I claim is:

1. A tree for boots and shoes comprising a flat casing adapted to fill up substantially the entire width of the footgear, a plate member 20 provided with a flat spiral thread housed therein, a handle upwardly extending through said casing for rotation of said plate member, a heel-piece pivotally secured to the rear of said casing, a rod extending forwardly through said casing, a toe-piece pivotally secured to said rod, and a rack formed on said rod meshing with said flat spiral thread.
2. In an extensible tree for boots and shoes, an operating member comprising a casing 30 adapted to fill up substantially the entire width of the footgear, a plate member rotatably housed therein, a flat spiral thread on one face of said plate member, a longitudinally sliding member projecting through the 35 wall of said casing provided with a rack meshing with said thread for expansion of the tree, and an operating spindle of said plate member projecting through the casing and adapted to be manually rotated.
3. In an extensible tree for boots and shoes 40 an operating member comprising a casing adapted to fill up substantially the entire width of the footgear, a horizontal plate member rotatably housed therein, a spindle for 45 said plate member projecting through said casing and terminating in a key for manual rotation, a flat spiral thread on said plate member, a longitudinally sliding member housed between guides in said casing and 50 projecting through the wall thereof, and a rack formed on said sliding member meshing with said spiral thread for altering the length of the tree.

In witness whereof, I have hereunto signed
55 my name this 15 day of September 1928.

HAMLET JOHN WILSON.
